SCRAPING AND CLEANING DEVICE

Wayne R. Hutter, Sanford, Mich., assignor to The Dow Chemical Company, Midland, Mich.

Filed June 1, 1971, Ser. No. 149,097

Term of patent 14 years

Int. Cl. D7—05
U.S. Cl. D49—23

FIG. 1 is a side elevation view of the scraping and cleaning device, showing my new design;

FIG. 2 is an elevation view looking from the right of FIG. 1;

FIG. 3 is an elevation view looking from the left of FIG. 1;

FIG. 4 is a cross sectional view taken along line 4—4 of FIG. 1;

FIG. 5 is an elevation view of a modified form of the scraping and cleaning device shown in FIG. 1 as seen from the right of FIG. 1; and

FIG. 6 is a top plan view of the modified scraping and cleaning device.

I claim:

The ornamental design for a scraping and cleaning device, as shown and described.
